UNITED STATES PATENT OFFICE.

FRANK EVANS AND DAVID DUTT, OF RIVERDALE, MICHIGAN, ASSIGNEES OF ONE-
THIRD TO BURTIS O. MARKHAM, OF RIVERDALE, MICHIGAN.

RAILWAY-SWITCH.

1,223,945.

Specification of Letters Patent. Patented Apr. 24, 1917.

Application filed September 23, 1915. Serial No. 52,174.

To all whom it may concern:

Be it known that we, FRANK EVANS and DAVID DUTT, citizens of the United States, and residents of Riverdale, in the county of 5 Gratiot and State of Michigan, have invented a new and Improved Railway-Switch, of which the following is a full, clear, and exact description.

Our invention relates to switches and signals adapted to be actuated by a train trip.

Our invention particularly relates to a switch and signal of the indicated type so constructed and arranged that the switch bar, connected with the switch points, will 15 be rocked by a train trip and a sliding axial movement will be given to the switch bar, the rocking movement serving to actuate a semaphore while the sliding movement serves to throw the switch points, the operation being automatically effected by a 20 train coming from either direction at any rate of speed.

Other distinguishing features of the invention will appear from the more specific 25 description following.

Reference is to be had to the accompanying drawings forming a part of this specification in which similar reference characters indicate corresponding parts in all the 30 views.

Figure 1 is a side elevation of a railway track equipped with our invention, the view including a train trip;

Fig. 2 is a plan view;

Fig. 3 is a fragmentary plan view on an enlarged scale of the operating devices of 35 a switch and signal;

Fig. 4 is a longitudinal vertical section on the line 4—4, Fig. 3;

Fig. 5 is a similar view on the line 5—5, 40 Fig. 3;

Fig. 6 is a transverse vertical section; and

Fig. 7 is a detail sectional side elevation 45 of the means for automatically rocking the switch bar.

Fig. 8 is a fragmentary plan view showing an obliquely grooved disk to be herein-after referred to.

Our invention is illustrated in connection 50 with a track, including a main track A, a siding B, and switch points C, the switch points being connected by tie-rods c.

A switch bar 10, is disposed transversely 55 beneath the switch points and connected

with the latter by suitable means here shown as consisting of clamp collars 11 on the switch bar 10, and plates 12, adjacent to the switch bar and suitably fastened to the switch points C. The switch bar 10, is 60 mounted to rock and slide axially in any suitable bearings 13.

In order to automatically rock the switch bar by an approaching train, the said switch bar has suitably connected therewith, a 65 rocker arm 14, which extends upwardly above the track and passes freely through a vertical opening 15, in an elongated link 16, which ranges longitudinally of the track. The engagement between the rocker arm 14, 70 and the link 16, is at the approximate center of said link. If desired, the arm 14, may have a slot 14^a, therein, through which a pin 15^a, extends to opposite side walls of the opening 15. One end of the link 16, is 75 pivoted as at 16^a, to a lever 17, said lever being fulcrumed at its lower end as at 18, on any suitable track support 19. The opposite end of the link 16, is pivoted as at 16^b, to the lower end of a similar lever 17^a, 80 which is fulcrumed at a point between its ends as at 18^a, in a bracket 19^a. Thus, as will be clear from Fig. 7, we provide means for an overslung and an underslung connection between the link and its respective levers 17, 17^a. Thus, when the lever 17^a, is tripped and rocked on its fulcrum by a locomotive approaching the same from the direction shown in Fig. 1 the link 16, will 85 be drawn toward said lever. On the other hand when the opposite lever 17, is tripped and rocked on its fulcrum by a train moving in the opposite direction, a pushing action will be exerted on the link. In connection with the switch bar and its operating levers and link, we provide means to trip said levers for closing or opening a switch by a train running in either direction at any rate of speed.

We prefer to employ a train trip 20, 100 which is hung on a hanger or other support 22, on a locomotive D, there being a compression spring 21, at the back of the trip 20 to cushion the shock. The hanger 22, as here shown, is suitably suspended from a 105 bellcrank 23, which is connected by a rod 23^a, and a hand lever 23^b, in the engine cab. The arrangement is such that upon the approach of a train carrying a trip 20, in either direction toward the switch, the said 110

trip will contact with the adjacent lever 17, 17^a thereby rocking the same and moving the link 16, longitudinally of the track, and through the connection with the rocker arm 5 14, turn the switch bar 10.

In order that the turning movement of the switch bar 10, may operate a signal, a semaphore 24, is provided, connected by any suitable means with the said switch bar. In the 10 example shown, a semaphore 24, is connected by a link 25^a with a vertical rod 25, slidably mounted in a signal stand 26, and extending vertically through the top 26^a, thereof. The lower end of the rod 25, connects 15 with the rockable switch bar 10, through the medium of a connecting rod 27, which is secured at its upper end to the rod 25, by a universal joint 28, the lower end of the connecting rod 27, having pivotal connection as 20 by a wrist pin 29, with the disk 30, on the said switch bar. It will thus be seen that a turning movement of the switch bar will serve to raise or lower the semaphore 24.

Simultaneously with the turning movement of the switch bar 10, the same is caused to slide axially, whereby to throw the switch points C. To effect the sliding movement, the disk 30, is constituted a worm element as 30 hereinafter explained and a fixed coacting worm element 31, is provided to engage the same. The element 31, is in the form of an arched bar, the ends of which are suitably fastened as at 32, to the track, with the said element 31, ranging obliquely across the periphery of the disk 30, said disk being provided with an oblique groove 33, thus giving said disk the character of a worm element, to receive the bar 31, as indicated in Fig. 5.

By the desired relation of the disk 30, and 40 the coacting element 31, it will be seen that upon a turning of the disk by the rocking of the switch bar 10, the engaging groove 33, therein and bar 31, will cause the said disk 30, and with it the switch bar 10, to be slid 45 axially in the bearings 13, thereby throwing the switch points c in unison with the operation of the semaphore 24. Thus the simultaneous sliding and turning movements are imparted to the switch bar 10, by a simple 50 and positively acting construction.

In order to lock the switch and signal, we provide a latch 34, which is pivoted to the track as at 35, to swing in a vertical plane. On the underside of the latch 34, between 55 the ends thereof, a catch tooth 36, is formed which is adapted to engage in a notch 37^a,

formed in a collar or enlargement 37, on the switch bar 10. A staple 38, is provided on the track, adapted to receive the latch 34, whereby a padlock 39, may be employed to 60 lock the switch.

In order to turn the rockable switch bar 10, manually when desired, a hand-wheel 40, or equivalent lever element, is provided on one end of the said switch bar. 65

The form and size of the opening 15, in the link 16, are such as to permit the arm 14, to move transversely relatively to said link 16, in response to the described sliding movement of the switch bar 10 by the action 70 of the worm elements 30, 31.

Having thus described our invention, we claim as new and desire to secure by Letters Patent:

1. In an apparatus of the class described 75 a transverse switch-bar, mounted to turn and to slide axially and provided with a rocker arm thereon, a longitudinally disposed link, there being a connection between said link and said rocker arm to rock the arm by a 80 longitudinal movement of the link and arranged to permit a transverse movement of the rocker arm with the switch bar relatively to the link, means connected with said link and adapted to be engaged by a train trip to 85 move the link longitudinally, and means to connect the switch bar with switch points to throw the latter by a longitudinal movement of the switch bar.

2. An apparatus of the class described, including a transverse switch bar mounted to turn and to slide axially and provided with a rocker arm thereon, a longitudinally ranging link, having between the ends thereof, an opening receiving the said arm on the switch bar, said opening being of a width to permit a movement of the said rocker arm transversely of the opening in response to a sliding movement of the switch bar, levers pivotally connected with the opposite ends of 100 the said link and adapted to be engaged by a train trip, and means to connect the switch bar with switch points. 95

In testimony whereof we have signed our names to this specification in the presence of 105 two subscribing witnesses.

FRANK EVANS.
DAVID DUTT.
